The ornamental design for an ultrasound cart, substantially as shown and described.

DESCRIPTION

FIG. 1 is a front perspective view of an ultrasound cart in accordance with the present design;

FIG. 2 is a rear perspective view thereof;

FIG. 3 is a front view thereof;

FIG. 4 is a right side view thereof;

FIG. 5 is a rear view thereof;

FIG. 6 is a left side view thereof;

FIG. 7 is a top view thereof; and,

FIG. 8 is a bottom view thereof.

The broken lines show portions of the ultrasound cart that form no part of the claimed design.
